UNITED STATES PATENT OFFICE.

GEORGE F. PARKER, OF ST. STEPHEN'S, CANADA.

IMPROVEMENT IN MOCCASINS.

Specification forming part of Letters Patent No. **146,399**, dated January 13, 1874; application filed August 9, 1873.

To all whom it may concern:

Be it known that I, GEO. F. PARKER, of St. Stephen's, in the Province of New Brunswick, Canada, have invented a new and Improved Boot-Moccasin; and I do hereby declare that the following is a full, clear, and exact description of the same, reference being had to the accompanying drawing forming a part of this specification.

The invention will be first fully described, and then pointed out in the claim.

Figure 1 represents an elevation of my improved boot-moccasin; and Figs. 2, 3, 4, 5, and 6, detail views of the several sections of which it is made.

The sole-piece C is made of an elliptical form, and sufficiently wide and long to form a seam with upper G and heel-piece E, which slopes from the leg-seam in opposite directions toward heel and toe, and is at some distance above the tread-face, as shown in Fig. 1, while the protuberance of seam is brought upon the outside, to make a smooth surface on the in-

side. The upper G of the sole has a tongue, g, and side projections g', to and under which is sewed the front piece H, the latter being made to overlap the heel-piece E and rear leg-piece I, to which it is sewed.

By constructing the boot of pieces that are thus shaped and fitted together, a very comfortable and durable moccasin is obtained, while the leather can be cut to more advantage and with greater economy, so as to make the boot cheaper, both to the trader and consumer.

Having thus described my invention, what I claim as new, and desire to secure by Letters Patent, is—

A boot-moccasin formed of the pieces C G E H I, put together substantially in the manner described.

GEORGE FLINT PARKER.
